UNITED STATES PATENT OFFICE.

STEPHEN P. M. TASKER, OF PHILADELPHIA, PENNSYLVANIA.

MACHINE FOR MAKING TUBES FROM HOLLOW INGOTS.

SPECIFICATION forming part of Letters Patent No. 331,581, dated December 1, 1885.

Application filed July 22, 1885. Serial No. 172,279. (No model.)

To all whom it may concern:

Be it known that I, STEPHEN P. M. TASKER, a citizen of the United States, residing in the city and county of Philadelphia and State of Pennsylvania, have invented certain Improvements in Machines for Making Tubes from Hollow Metal Ingots and for Reducing Tubes or Rods, of which the following is a specification.

10 Apart from the intended employment of my machine for reducing and also for straightening tubes and rods, the object of my invention is the manufacture of a tube from a hollow cylindriform metal ingot by rolling, either hot or cold, by means of the machine herein-after described, the said ingot down and out upon a mandrel at least of the required length of the tube to be formed, thereby compacting and consolidating the substance of the metal 20 of the ingot, thinning or reducing the latter in thickness and elongating it until the required proportions are attained. The ingots which I employ are tubular or of a hollow cylindriform structure, of any metal, and either open 25 at both ends, closed at one end, or closed at one end and provided through such closed end with an aperture for the traction-rod of a mandrel.

As my machine is of especial applicability to the making of steel tubes, I contemplate also 30 the employment of a steel cast ingot of a character invented by me, two applications for patents for which were filed in the United States Patent Office upon the 14th day of May, 1885, and respectively numbered 165,695 and 35 165,696.

Heretofore in the art of metal-rolling two or more pairs or sets of equal-sized concave-faced rolls, the two rolls constituting the respective sets or pairs of which being placed the one 40 over the other, have crossed each other—that is to say, have been adjusted in such manner that vertical planes respectively projected from their respective longitudinal axes have intersected each other at other than a right angle—have been in successive disposition in the same machine employed for rounding, straightening, and sizing tubes and rods, the said tubes or rods having been passed through the passes of the successive sets in a direction 45 which may, for the purpose of explanation, be described as right angular to a common imaginary longitudinal axis of each pair of rolls,

or in a direction much more nearly right angular to than parallel with the longitudinal axis of each individual roll of each pair. Heretofore, also, in the art of metal-rolling two or three equal-sized rolls having concave working-faces have been arranged in a suitable housing obliquely side by side or one over the other, or spirally, as it were, around a 50 common central imaginary longitudinal axis of the set, so that the axes of the respective rolls forming such set have been inclined to each other in different planes, and each and all at an angle to the said common longitudinal axis, which is that of the article to be rolled, the said article having been introduced through a pass extending longitudinally between or through, so to speak, the rolls, (which pass, as is well known, is an extended 55 straight bearing obtained between the roll-faces in a line bisecting the angle of inclination of the rolls,) and the said machine as such having been employed for rolling, finishing, reducing, straightening, and smoothing rods, 60 tubes, shafting, and other cylindrical or tubular articles, which receive a spiral or combined rotary and progressive movement from the rolls, which all revolve in the same direction, and not only form the article to a true 65 cylindrical shape, but at the same time feed it 70 forward.

I am not aware that sets of rolls arranged in the foregoing manner have been arranged in series.

Assuming a set of rolls of the character last 85 above described as a given type, I may assume a set of rolls of the character first above described as another given type, and may define the distinguishing characteristic of the two 90 types to be the direction in which the article to be rolled is passed through the set of rolls—that is to say, whether it be passed through them in a direction right angular to what we may term their "common axis," as in the case 95 of the rolls first described, or parallel or coincident with said common axis, as in the case of the rolls last-above described.

I have discovered that a superior merchantable tube of metal, but especially that a steel 100 tube, can be economically and successfully manufactured either from a tubular metal ingot, or especially from a hollow steel cast ingot, and also that a tube or rod of metal can

be successfully reduced in diameter or straightened by the employment of a machine consisting of a series of sets of concave-faced rolls, the rolls of each of which sets are a series composed of three or more rolls arranged at an angle to each other, and each roll at a common angle to its neighbor, so that the concave surfaces of all of the rolls form a circular pass, and in passing over the surface of the tube or rod hug it like a swage and touch it at every part, the reducing passes of which sets are successively smaller, the rolls of which sets may, if desired, be successively arranged so as to break joints and thereby act upon every portion of the surface of the article to be rolled, and all of which rolls are idler-rolls and are adapted to be revolved in opposite directions by the friction of the article passed through them.

In employing the foregoing machine for making tubes from ingots a mandrel adapted to be rotated with the ingot upon it, and at least of the required length of the tube to be formed from said ingot, is passed through the passes of the sets in a direction right angular to their common "face plane" or "axis," as I for convenience term it, upon which mandrel the substance of the metal of the ingot is by the rolls compacted and consolidated, and the ingot itself thinned or reduced in thickness and elongated until the required proportions are attained. A rod or tube to be reduced or straightened is also passed through in a similar direction.

Apparatus embodying a good form of my invention is represented in the accompanying drawings, and described in this specification, the particular subject-matter claimed as novel being hereinafter definitely specified.

In the accompanying drawings, Figure 1 is a face elevational end view of a set of rolls embodying my invention and composed of a series of three similarly-inclined overlapping rolls of the character hereinafter described, sight being taken in a direction right angular to the common face plane or axis of the set. The view is in the nature of a fragmentary detail, but part of two of the rolls being shown. The view also represents in section, not, however, to exactly correct proportions and curvatures, the two opposite segmental framing-plates, in connection with which the roll, which is shown completed, is housed, together with boxings for the journals of the said roll and an adjusting-arm connected with one of said boxings. Fig. 2 is a perspective view of an apparatus embodying my invention and composed of a series of two sets of rolls, each of which sets is composed of three rolls, and is of the character represented in Fig. 1. Fig. 3 is a central vertical longitudinal side sectional elevation through the apparatus of Fig. 2, one of the rolls of each set, however, not being shown in section. Fig. 4 is a perspective view of one of the sets of rolls represented in Figs. 2 and 3, sight being, however, taken from the opposite side from that from which

sight in Fig. 2 is taken, and the set represented being the first set of rolls or that the rolls of which are lettered D. Fig. 5 is a fragmentary partially sectional partially elevational detail of a rotatable mandrel which I find it convenient to employ when employing my machine for making tubes from hollow metal ingots.

Similar letters of reference indicate corresponding parts.

In the drawings, A represents any suitable bed or foundation for supporting the housings within which the rolls are journaled.

T is a tube, the direction of movement of which is represented by the arrow in the drawings.

In the drawings no representation is made of any means for handling or, if desired, for occasioning the advance or retraction of the tube, for the reason that I assume such representation to be unnecessary, as any device for manipulating the tube into the passes of the rolls is adapted for employment. Some such device is, however, to be employed.

B B are a series of transverse vertical standards, between which are disposed frame-plates C, for supporting the boxings or bearings or the journals or axles of the rolls, and which in the region of their support of said bearings or journals are conveniently curved, so as to be of suitable segmental form to facilitate a movement of the boxings or journals of the rolls for the adjustment of said rolls.

In the form of apparatus shown, in which there are three rolls to the set, there are conveniently six frame-plates between each pair of standards, the frame-plates and standards together constituting simply a framing for the support of the rolls. The housings in the form of apparatus shown in the drawings—and it is to be borne in mind that the series of sets may contain a greater number of sets of rolls than two—support two successively-placed sets of rolls having a series composed of three rolls to a set, the rolls of the first of which sets are marked D, and the rolls of the second of which sets E. The passes of the successive sets are successively of smaller diameter. This is conveniently effectuated in the following manner: The three rolls of each set are relatively of the same size, but the concave working-surfaces of the two rolls of the second set are more filled in, so to speak, than the working-surfaces of the rolls of the first set—that is to say, the diameter of the central portions of the rolls of the second set is greater than that of the rolls of the first set, so that the normal pass of the second set is diametrically smaller than the normal pass of the first set. This normal relation of diminishing passes is to be preserved, whatever number of sets of rolls happens to be employed. The rolls of each set are respectively inclined at an angle to each other, (it being preferable that the angle should be as slight as possible), so that the axis of each roll is inclined with respect to the axis of the adjoining rolls, and the axis of each roll

possesses an inclination corresponding to that of the axis of every other roll. The rolls, therefore, may be said to similarly overlap. Their relative positions, from which there can be no departure except by mutual adjustment, are fully represented in Fig. 1 of the drawings.

The journaling or mounting of the rolls of each set, and the means for adjusting the rolls of each set are, preferably, precisely similar throughout any number of sets which may be employed. I will, therefore, describe the same with reference to but one set of rolls—viz., the first. Each roll is, as stated, concave as to its central portion or acting face, to which face or portion the letters D are in Fig. 1 shown applied. Each roll is on each end beyond its central portion prolonged, and the prolongations together constituting shafts of the roll are composed of conical portions d' and cylindrical portions d'' . Beyond the said cylindrical portions each roll is provided with journals or axles d'' ; all as clearly represented in said Fig. 1.

In the second set of rolls the letters $e' e'' e''$, respectively designate the conical portions, the cylindrical portions, and the journals of the rolls E of said second set. The journals are conveniently incased in boxings F, which are mounted so as to have a movement in slots or ways G, formed in the frame-plates of the housing. If desired, the boxings can be dispensed with and the journals be simply entered within said slots. I prefer, however, to employ boxings. The curvature of the segmental portions of the frame-plates is similar as to all the plates, and struck from a radius equal to one-half of the length of each roll, so that the length of each roll between its frame-plates is conveniently equal to a diametric line between two opposite frame-plates, which support a given roll. The rolls of each set are so mounted that their conical portions respectively face, as represented in Fig. 1.

In order conveniently to effectuate the movement of the rolls so as to slightly alter their relative angular disposition, and thereby enlarge or contract the diametric extent of the pass formed between them, I have connected with each boxing or with the axles of the rolls an adjusting-arm, H, which is conveniently passed through a slotted flange, I, erected from or connected with a frame-plate, the said arm being threaded and provided with lock-nuts i, whereby the arm, and consequently the boxings and the journals of the rolls, can be locked in predetermined adjusted positions.

In the drawings, for clearness of illustration I have represented the adjusting-arms as applied to but one end of each roll. It is, however, to be understood that they are applied to each journal or boxing of each end of each roll. By virtue of the slots or ways in the said metal frame-plates and the adjusting-arms, the movement of the rolls of each set for increasing or diminishing the diameters of their passes becomes both certain and easy. The slots or

ways in opposite frame-plates are disposed at a slight angle to each other so as to facilitate the movement of the rolls in adjustment.

A suitable arrangement or disposition of the frame-plates and the slots therein is represented in the drawings.

The slots or ways for the journals of the rolls and the nut-provided adjusting-arms connected with the axle-boxings in said ways, together constitute simply a composite roll-adjusting contrivance, the office of which is to permit of and render easy the adjustment of any given set or of all the sets of rolls at different relative angles, so that the rolls may approach more closely together or separate so as to increase or diminish the diametric extent of the passes between them and adapt them for employment with tubes or rods of varying diameters. Any other adjusting device operating to a similar result may, however, be substituted in the stead of the foregoing. When axle-boxings are not employed, means for retaining the journals of the rolls in fixed positions must be applied direct to the journals. The tube, rod, or other article which is passed through the rolls actuates them, and is rapidly and evenly reduced, the whole rolling surface of each roll bearing upon the said tube, touching it at every part, rolling out inequalities and causing it to take on a spiral progressive motion in its passage through the machine.

When my machine is employed for making tubes by using in connection with it a mandrel, P, at least as long as the tube to be formed, the said mandrel is conveniently adapted to be rotated by being swiveled in a mandrel-head, Q, Fig. 5, which is actuated to its advance or retraction by any such means as are well known to iron-masters.

O are bell-mouths for guiding the tube in its passage through the machine.

Having now described what I believe to be a convenient embodiment of my invention, and at the same time described the operation of the machine, it is proper for me to add that I believe myself to be the first to use a mandrel capable of rotation about its longitudinal axis, and of the length of the tube which is to be produced in conjunction with a series of sets of three or more correspondingly angularly disposed or overlapping concave-faced idler-rolls having by sets successively diminishing passes, by which arrangement it is possible to reduce the external diameter of an ingot placed upon the mandrel, and, if desired, by adjusting the rolls after each pass to effect a continued reduction until said ingot becomes a tube of the desired thickness of substance and of no greater length than the mandrel.

It is of course obvious that while the housing for containing, and the means for retaining the adjusted rolls, which I have represented and described, are well adapted for the purpose yet that they are not essential to my invention. The special adjusting devices de-

scribed or others operating to substantially the same result, however, permit of the adjustment of the rolls to accommodate any size of article to be rolled within their range of separation. It is, however, proper to state that although I have herein recited as the best construction, that the concave working-surfaces of the rolls of the second set should be more filled in than the working-surfaces of the rolls of the first set—that is to say, should be of greater diameter at their central portions than the rolls of the first set, and so on throughout the series—yet that all of the rolls of all of the sets may, if desired, be of the same diameter, and the successively diminishing diameters of the passes be secured simply by the adjustment of the rolls of each succeeding set of rolls.

The spiral or revolving progressive motion to which an ingot on a mandrel and with it the mandrel to which it for the time being adheres, or to which a tube or rod under process of reduction is subjected, prevents finning or irregularities of any kind, and therefore tends to produce a uniformly cylindric and very marketable product.

When a mandrel is employed, it may be extracted from the tube after rolling by stretching the tube by loosening the mandrel, and by extracting the latter by any suitable means.

It is obvious that my machine is to be distinguished from a machine of the class hereinbefore referred to in which two or three equal-sized rolls having concave working-faces have been arranged in a suitable housing obliquely side by side, or one over the other, or spirally, as it were, around a common central imaginary longitudinal axis of the set, and in which the pass of the set is extended longitudinally between or through, so to speak, the rolls, as in machines of the foregoing class, the bearings being only, as to each roll, upon a line, and each roll revolving in the same direction, the capacity for reduction is reduced to a minimum and the machine adapted for straightening only, whereas, in my machine in which the rolls are disposed at as small an angle as possible, the rolls, as to their acting faces, completely encircle the tube and maintain it as if in a swage, instead of biting upon it in a series of longitudinal straight lines of pressure between which lines there is no contact of the rolls with the tube, so that there is nothing to prevent the tube from spreading between the said lines of bite.

My rolls act in reducing the metal much as the rolls of ordinary rollings-mills, with, however, the advantage of a revolution being imparted to the tube so as to cause the uniform reduction and truing of its surfaces. While it is preferable that the passes of the succeeding sets should successively diminish—that is to say, diminish in strict consecution, set by set and without variance, omission, or alternation—yet all the results which flow from consecutive diminution may be obtained by making, for instance, two consecutive or ad-

joining sets of a given and the same diameter of pass, by making the two immediately succeeding consecutive or adjoining sets of a lesser but of the same diameter of pass, and by making the two further immediately succeeding consecutive or adjoining sets of a still lesser but of the same diameter of pass. This arrangement, or one kindred to it—the number or series of sets of similar diameter of pass employed not being vital—is not desirable, but it is manifestly embraced within my invention, and the terms "successive" or "gradual" diminution herein employed are not to be understood as employed with literal exactness.

While I have represented and herein described each set of the rolls as being composed of a series consisting of but three rolls, it is yet proper for me to state that I do not restrict myself to the employment of a series consisting of but three rolls, as it will be obvious to any mechanic that four, five, or even a greater number of rolls may be, under suitable modifications of housing and means of adjustment, employed to produce the same result as that which I obtain by the use of the said three rolls. Of course many minor changes in the mounting and mode of adjustment of the parts would have to be resorted to, but, as is obvious, the feature of a series of sets of concave-faced rolls, all of the rolls of which are arranged at an angle to each other, and each roll at a common angle to its neighbor, so that the concave surfaces of all of the rolls form a circular pass through which the article to be rolled is passed in a direction right-angular to the common face, plane, or axis of the set, and all of which rolls are adapted to revolve in opposite directions, which is the most important feature of my invention, would be preserved in any such arrangement of increased series.

I do not claim or seek herein to cover in connection with the other features of invention the provision of positive mechanism for driving the sets of rolls, as such mechanism, in connection with an apparatus of this character, is made the subject of an application which I have designated as "Case C, No. 4," and executed and filed contemporaneously with this. I do not, moreover, claim herein the housing provided with the segmental framing-plates, nor, again, the roll-adjusting devices, as these features constitute the subject-matter of another application contemporaneously executed and filed, and designated by me as "Case C, No. 1."

Having thus described my invention, I claim—

1. In a machine for making tubes from hollow metal ingots, or for reducing tubes or rods of metal, the combination of a series of sets of concave-faced rolls, each of which sets consists of a series of three or more rolls arranged at an angle to each other, and each roll at a common angle to its neighbors, so that the concave surfaces of all of the rolls form a circular pass,

through which the article to be rolled is passed in a direction right angular to the common axis of each set, the passes of such sets diminish successively in diameter and all of such rolls revolve in opposite directions, with suitable means for advancing and retracting the article to be rolled through the passes of the series of sets in a direction right angular to the common axis of each set of rolls, substantially as set forth.

2. In a machine for making tubes from hollow metal ingots, or for reducing tubes or rods of metal, the combination of a series of sets of concave-faced rolls, each of which sets consists of a series of three or more rolls arranged at an angle to each other, and each roll at a common angle to its neighbors, so that the concave surfaces of all the rolls form a circular pass, through which the article to be rolled is passed in a direction right angular to the common axis of each set, the concave working-faces of the rolls of each succeeding set of such series are more filled in and of greater diameter than the rolls of the set immediately preceding, so that the passes of the sets gradually diminish in diameter, and all of such rolls revolve in opposite directions, with suitable means for advancing and retracting the article to be rolled through the passes of the series of sets in a direction right angular to the common axis of each set of rolls, substantially as set forth.

3. In a machine for making tubes from hollow metal ingots, or for reducing tubes or rods of metal, the combination of a series of sets of concave-faced rolls, each of which sets consists of a series of three or more rolls arranged at an angle to each other, and each roll at a common angle to its neighbors, so that the concave surfaces of all the rolls form a circular pass, through which the article to be rolled is passed in a direction right angular to the common axis of the set, the passes of such sets diminish successively in diameter, and all of such rolls revolve in opposite directions, frame-plates for the journals of the rolls of each set, the arrangement being thereby such that each set of rolls is capable of an independent adjustment, and suitable means for advancing and retracting the article to be rolled through the passes of the series of sets in a direction right angular to the common axis of each set of rolls, substantially as set forth.

4. In a machine for making tubes from hollow metal ingots, or for reducing tubes or rods of metal, the combination of a series of sets of concave-faced rolls, each of which sets consists of a series of three or more rolls arranged at an angle to each other, and each roll at a common angle to its neighbors, so that the concave surfaces of all the rolls form a circular pass, through which the article to be rolled is passed in a direction right angular to the common axis of the set, the passes of such sets diminish successively in diameter, and all of such rolls revolve in opposite directions, frame-plates for the journals of the rolls of each set,

means for securing the fixed adjustment of the journals of the rolls with respect to their frame-plates, the arrangement being thereby such that each set of rolls is capable of an independent adjustment, and suitable means for advancing and retracting the article to be rolled through the passes of the series of sets in a direction right angular to the common axis of each set of rolls, substantially as set forth.

5. In a machine for making tubes from hollow metal ingots, or for reducing tubes or rods of metal, the combination of a series of sets of concave-faced rolls, each of which sets consists of a series of three or more rolls arranged at an angle to each other, and each roll at a common angle to its neighbors, so that the concave surfaces of all the rolls form a circular pass, through which the article to be rolled is passed in a direction right angular to the common axis of the set, and the concave working-faces of the rolls of each succeeding set of such series are more filled in and of greater diameter than the rolls of the set immediately preceding, so that the passes of the sets gradually diminish in diameter, and all of such rolls revolve in opposite directions, frame-plates for the journals of the rolls of each set, means for securing the fixed adjustment of the journals of the rolls with respect to their frame-plates, the arrangement being thereby such that each set of rolls is capable of an independent adjustment, and suitable means for advancing and retracting the article to be rolled through the passes of the series of sets in a direction right angular to the common axis of each set of rolls, substantially as set forth.

6. In a machine for making tubes from hollow metal ingots, or for reducing tubes or rods of metal, the combination of a series of sets of concave-faced rolls, each of which sets consists of a series of three or more rolls arranged at an angle to each other, and each roll at a common angle to its neighbors, so that the concave surfaces of all the rolls form a circular pass, through which the article to be rolled is passed in a direction right angular to the common axis of the set, the passes of such sets diminish successively in diameter, and all of such rolls revolve in opposite directions, slotted segmental frame-plates for the journals of the rolls of each set, adjusting-arms connected with the journals of the rolls of each set and with the framing, the arrangement being thereby such that each set of the rolls is capable of an independent adjustment, and suitable means for advancing and retracting the article to be rolled through the passes of the series of sets in a direction right angular to the common axis of each set or pair of rolls, substantially as set forth.

7. In a machine for making tubes from hollow metal ingots, or for reducing tubes or rods of metal, the combination of a series of sets of concave-faced rolls, each of which sets consists of a series of three or more rolls arranged at an angle to each other, and each roll at a

common angle to its neighbors, so that the concave surfaces of all the rolls form a circular pass, through which the article to be rolled is passed in a direction right angular to the common axis of the set, and the concave working-faces of the rolls of each succeeding set of such series are more filled in and of greater diameter than the rolls of the set immediately preceding, so that the passes of the sets gradually diminish in diameter, and all of such rolls revolve in opposite directions, slotted segmental frame-plates for the journals of the rolls of each set, means for securing the fixed adjustment of the journals with respect to the frame-plates, the arrangement being thereby such that each set of rolls is capable of an independent adjustment, and suitable means for advancing and retracting the article to be rolled through the passes of the series of sets in a direction right angular to the common axis of each set of rolls, substantially as set forth.

8. In a machine for making tubes from hollow metal ingots, or for reducing tubes or rods of metal, the combination of a series of sets of concave-faced rolls, each of which sets consists of a series of three or more rolls arranged at an angle to each other, and each roll at a

common angle to its neighbors, so that the concave surfaces of all of the rolls form a circular pass, through which the article to be rolled is passed in a direction right angular to the common axis of the set, and the concave working-faces of the rolls of each succeeding set of such series are more filled in and of greater diameter than the rolls of the set immediately preceding, so that the passes of the sets gradually diminish in diameter, and all of such rolls revolve in opposite directions, slotted segmental frame-plates for the journals of the rolls of each set, adjusting-arms connected with the journals of the rolls of each set and with the framing, the arrangement being thereby such that each set of the rolls is capable of an independent adjustment, and of suitable means for advancing and retracting the article to be rolled through the passes of the series of sets in a direction right angular to the common axis of each set of rolls, substantially as set forth.

In testimony whereof I have hereunto signed my name this 17th day of July, A. D. 1885.

STEPHEN P. M. TASKER.

In presence of—

J. BONSALL TAYLOR,
JOHN JOLLEY, Jr.

It is hereby certified that in Letters Patent No. 331,581, granted December 1, 1885, upon the application of Stephen P. M. Tasker, of Philadelphia, Pennsylvania, for an improvement in "Machines for Making Tubes from Hollow Ingots," errors appear in the printed specification requiring correction, as follows: On page 5, in lines 3 and 21, the word "each" should read *the*; same page, in lines 3, 5, 22, 26, 43, 45, 64, 89, 93, 115, and 117, and on page 6, lines 6, 10, 34, and 38, the word "such" should read *which*; and that the Letters Patent should be read with these corrections therein that the same may conform to the record of the case in the Patent Office.

Signed, countersigned, and sealed this 24th day of August, A. D. 1886.

[SEAL.]

D. L. HAWKINS,
Acting Secretary of the Interior.

Countersigned:

R. B. VANCE,
Acting Commissioner of Patents.
